UNITED STATES PATENT OFFICE.

HARRY LEVY, OF CHICAGO, ILLINOIS.

BATHTUB COVER.

Application filed May 4, 1927. Serial No. 188,784.

My invention relates to appliances for covering bathtubs and the like to prevent the settling of dust and other foreign matter therein, and my main object is to provide a cover of this kind which maintains the bathtub in clean condition and therefore in readiness for immediate use at any time.

A further object of the invention is to provide an installation for the novel cover in connection with the bathtub, so that the cover may be in a handy position at all times.

A still further object of the invention is to provide a novel housing means for the cover, in order that it may be concealed and out of the way when not in use.

Another object of the invention is to have the cover designed on the principle of a window shade, for instant spreading upon the bathtub when desired, as well as for instant concealment when not to be used.

Another important object of the invention is to so construct the cover installation that it will be entirely out of the way when the bathtub is to be used.

A final, but nevertheless significant object of the invention is to construct the same with few and simple parts, in order that it may be readily handled by any one and produced inexpensively.

With the above objects in view and any others that may suggest themselves from the specification and claims to follow, a better understanding of the invention may be gained by reference to the accompanying drawing, in which—

Figure 1 is a plan view of the novel cover as used;

Fig. 2 is a section of a typical bathtub showing the position of the cover when not in use; and

Fig. 3 is an enlarged longitudinal section of the main portion of the appliance.

Referring specifically to the drawing, 5 denotes a bathtub of conventional design, which has the rim rolled as indicated at 6. In applying the novel cover, I use the ends of the bathtub rim as a base for attaching the same. The cover is preferably constructed of two sheets 7 of washable duck or other substantial cloth, these sheets being adapted to issue from cylindrical housings 8 mounted on the ends of the bathtub. 55 These housings are preferably attached to the rim 6 by spring clips 9, which are, of

course, easily flexed and released in case the removal of the housings is desired.

Inside of each housing is journaled a roller 10 of the spring window shade type, 60 on which the corresponding cover sheet 7 is wrapped. When the sheet is to be extended, it issues through a longitudinal slot 11 in the inner side of the housing and assumes a position immediately above the bathtub 65 rim, so that when the sheets or sections 7 have been drawn to meet at a medial point as indicated in Figure 1 they will lie upon the entire crown of the rim 6 and therefore exclude dust and dirt when the bathtub is 70 not to be used.

In order that the cover sections 7 may be held together when extended, any suitable coupling means may be used which is capable of being readily released, if desired. 75 However, I prefer at this time to employ the simple device more clearly illustrated in Figure 3. In this embodiment, the left-hand cover section carries a transverse tube 12, and the right-hand cover section carries a similar rod 13 from which extends a pair of 80 spring clips or jaws 14 which are adapted to engage the tube 12 when the cover sections are assembled, holding the sections together by spring tension. The rod 13 is, of course, 85 a reinforcing agent as well; and the tube 12 and the upper clip or jaw 14 carry cooperating handles 15 for use by the attendant when the cover sections are to be assembled or separated.

It will be seen that the novel cover forms a simple and efficient means for protecting the bathtub from foreign matter. As long as the cover is in place the bathtub remains in clean condition and is therefore in readiness for immediate use in case one should desire to take a bath, without the necessity of cleaning or washing the dust, dirt or other foreign matter from the surface of the tub, especially when one's time is limited. 100 The cover may be quickly assembled in place; yet, by a simple motion the sections may be uncoupled, in which event they will depart in the direction of their respective housings, and become concealed therein, so that the cover will be out of the way. With the parts properly designed, the appliance should present a compact and neat appearance at all times, and especially when the cover sections are concealed, in which event 105 the housing assemblies will not appear unsightly or be in the way of the occupant 110

when the bathtub is in use. To improve the appearance of the housings and other fittings they may be enameled in white, so as to harmonize with the appearance of the 5 bathtub and suggest sanitation.

As a modification, I might suggest that the cover may be made in one length, so as to require but one housing. However, this is a secondary consideration, as may 10 be many other improvements and refinements which my invention may be susceptible of; and all such improvements and refinements which may arise in the development of the structure I desire to consider 15 as coming within the spirit and scope of my invention as covered by the appended claims.

I claim:

1. A cover for bathtubs comprising housings mounted on opposed sections of the 20 bathtub rim, and sheets extensible from the respective housings to meet and cover the bathtub.

2. A cover for bathtubs comprising housings removably mounted on opposed sections 25 of the bathtub rim, and sheets extensible from the respective housings to meet and cover the bathtub.

3. A cover for bathtubs comprising housings mounted on opposed sections of the 30 bathtub rim, tensioned devices to secure the housings to the rim, and sheets extensible from the respective housings to meet and cover the bathtub.

4. A cover for bathtubs comprising housings mounted on opposed sections of the 35 bathtub rim, spring clips to secure the housings to the rim, and sheets extensible from the respective housings to meet and cover the bathtub.

40 5. A cover for bathtubs comprising cylindrical housings mounted on opposed sections of the bathtub rim, spring rollers journaled in said housings, sheets wound upon the rollers and extensible from the housings to

meet along the level of the bathtub rim, 45 and a coupling element at the meeting site of the sheets to keep them together.

6. A cover for bathtubs comprising cylindrical housings mounted on opposed sections of the bathtub rim, spring rollers journaled in said housings, sheets wound upon the rollers and extensible from the housings to 50 meet along the level of the bathtub rim, and cooperating coupling elements carried by the sheets along their contiguous 55 edges.

7. A cover for bathtubs comprising cylindrical housings mounted on opposed sections of the bathtub rim, spring rollers journaled in said housings, sheets wound upon the 60 rollers and extensible from the housings to meet along the level of the bathtub rim, and spring coupling elements carried by the sheets along their contiguous 65 edges.

8. A cover for bathtubs comprising cylindrical housings mounted on opposed sections of the bathtub rim, spring rollers journaled in said housings, sheets wound upon the rollers and extensible from the housings to 70 meet along the level of the bathtub rim, a reinforcing element carried by one of the sheets, and spring jaws carried by the other to engage the said reinforcing element.

9. A cover for bathtubs comprising cylindrical housings mounted on opposed sections 75 of the bathtub rim, spring rollers journaled in said housings, sheets wound upon the rollers and extensible from the housings to meet along the level of the bathtub rim, a reinforcing element carried by one of the sheets, spring jaws carried by the other to 80 engage the said reinforcing element, and handles carried by the reinforcing element and one of the spring jaws respectively for the manipulation of the sheets. 85

In testimony whereof I affix my signature.

HARRY LEVY.
